(57) **CLAIM**

I claim the ornamental design for a headphone, as shown and described.

DESCRIPTION

The patent or application file contains at least one drawing executed in color. Copies of this patent or patent application with color drawing(s) will be provided by the Office by request and payment of the necessary fee.

FIG. 1 is a perspective view of a first embodiment of a headphone, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of a headphone, the second embodiment being similar to the first embodiment except that the stippling is used to indicate a difference in color within the headphone;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and

FIG. 14 is a bottom plan view thereof.

FIG. 15 is a color, perspective view of a third embodiment of a headphone, the third embodiment being similar to the first except that areas of certain colors are indicated within the design;

FIG. 16 is a color, front elevational view thereof;

FIG. 17 is a color, rear elevational view thereof;

FIG. 18 is a color, left side elevational view thereof;

FIG. 19 is a color, right side elevational view thereof;

FIG. 20 is a color, top plan view thereof; and,

FIG. 21 is a color, bottom plan view thereof.

Broken lines are for illustrating portions of the headphone which form no part of the claimed design.

Stippling is used to indicate a difference between color throughout the design.
